UNITED STATES PATENT OFFICE.

JACK STANSFIELD PICKFORD, OF WEYMOUTH, ENGLAND.

HAIR COMB.

Application filed February 26, 1926, Serial No. 90,720, and in Great Britain April 24, 1925.

My invention relates to hair-combs of the type comprising a plurality of substantially parallel rows of teeth or comb-units arranged side by side for use in imparting a 5 wave to and/or otherwise treating the hair.

An important feature of the present invention is to provide an improved construction of comb of this type so that the hairs as they are being combed shall be rubbed by 10 more than one tooth while the comb is passing through them.

According to this invention, the hair-comb comprises in combination at least three substantially parallel rows of teeth arranged 15 side by side and held close together solely along the back of the comb with the teeth of one row spaced apart beyond the roots from the teeth of an adjacent row to provide between each two contiguous rows a longitudinal channel extending from the tips of the teeth to a situation at the roots. If desired, the rows of teeth may be integral with one another along the back of the comb. The comb is of rigid and neat appearance, and 20 the spaces between the rows of teeth enable the hair to be properly deflected without binding or breaking on the teeth, the latter being preferably so arranged that no single hair can pass through the comb without 25 being rubbed or curved in the process. The hairs are cleaned and polished and a wave is imparted to them.

A further feature of the invention consists in providing a means carried by the 35 comb, such as an electric heater in the back of the comb, for the purpose of heating the comb so that the wave imparted to the hair may be set, and according to a still further feature of the invention, one or more of the 40 teeth or rows of teeth may be hollow for communication with a reservoir, which may be in the back of the comb, so that hair lotions or tonics may be conveyed to the scalp.

The combs may be of any desired suitable 45 material and may be built up of separate toothed units, or they may be moulded or cast or otherwise formed in one piece.

Several embodiments of combs made in accordance with this invention are shown in 50 the accompanying drawing in which:

Figure 1 is a side view of a comb, with parts broken away;

Figure 2 an end view of this comb;

Figure 3 a view similar to Figure 1 showing another comb;

Figure 4 an end view of a comb;
Figure 5 a view similar to Figures 1 and 3 showing a further modification;

Figure 6 an end view of a comb;

Figure 7 an end view of a modification; 60

Figure 8 a side view of a different type of comb with parts broken away, the teeth being arranged according to any of the preceding embodiments.

In the constructions shown in Figures 65 1-5 three comb elements 1, 2 and 3 are secured together in any suitable manner as by the rivets 4 or screws 5, in which latter case the elements are readily separable for cleaning purposes. The comb elements may be 70 made integral if desired as shown in Figure 6 with a solid back portion 6, and in the case of separate elements they may be suitably formed, as shown in Figures 2 or 4, to obtain the required spacing of the 75 teeth and the desired finish for the back. In the embodiment shown in Figure 1 the teeth of the centre row are inclined and are of greater pitch than the outside rows, each of which has perpendicular teeth. In the 80 embodiment shown in Figure 3 the teeth in each row are perpendicular but those in the centre row are staggered in relation to those in the outer rows; the pitch of the teeth in each row being the same. 85

Owing to the hair having to pass round the teeth of the centre row which are out of line with the teeth of the outer rows, the hair is well rubbed on all sides and is thoroughly cleaned and polished from the roots 90 to the free ends. The three rows of teeth passing through the hair also separate the individual hairs thus making the hair more fluffy and loose.

In the embodiment shown in Figure 5 95 half the teeth of the centre row are perpendicular and half inclined.

In all the embodiments above described, the tips of the teeth may lie on a curve approximating to the curvature of the head, and the teeth of the outside rows preferably project slightly beyond those of the centre row to facilitate entry into the hair. The separate comb elements may be hinged together if desired along the back edge or along one end so that they may be opened out for cleaning purposes; a clip or other suitable device being provided to hold the elements together in closed position for use. 100 Figure 7 illustrates one such arrangement 105 110

in which it will be seen that the comb elements 1, 2 and 3 are hinged together at 50, the hinge extending along the back of the comb, and a clip 51 is provided for holding the comb elements in their closed operative position. In this arrangement it will also be observed that a clearance is provided between the comb elements extending to the roots of the teeth. In any of the previously 10 described combs the elements may be similarly arranged.

Figure 8 shows a comb in which the separate comb elements 1, 2 and 3 are detachably secured in a backing 7 by the screws 5 and 15 a handle 8 is hinged at 9 so as to fold over on to the comb elements when desired. A small spring clip 10 is provided to hold the handle in its operative position.

In any of the embodiments of this invention 20 the tips of the teeth may follow a curve approximating to the curvature of the head. Also, it will be appreciated that the teeth in the various elements in the different 25 modifications may be variously shaped and arranged to give the desired effect. While certain specific examples have been shown in the drawing, it will be understood that the invention is not limited to the same, for various arrangements of the teeth are 30 possible which would provide a comb capable of obtaining a drag on single hairs which is a desirable feature of the comb according to this invention.

I claim:

35 1. In a hair-comb the combination with the back, of at least three substantially parallel rows of teeth arranged side by side and held close together solely along the back of the comb, the teeth of one row being spaced 40 apart beyond the roots from the teeth of an adjacent row to provide a longitudinal channel extending between each two contiguous rows from the tips of the teeth to a situation 45 at the roots of the teeth, the outer rows having longer teeth than those of at least one inner row.

2. In a hair-comb the combination with the back, of at least three substantially parallel rows of teeth arranged side by side and held close together solely along the back of the comb, the teeth of one row being spaced 50 apart beyond the roots from the teeth of an adjacent row to provide a longitudinal channel extending between each two contiguous rows from the tips of the teeth to a situation 55 at the roots of the teeth, each of at least two of said rows having the tips of its teeth arranged in a curved line having its concavity facing away from the back of the comb.

60 3. In a hair-comb comprising the combination with the back, of at least three substantially parallel rows of teeth arranged side by side and held close together solely

along the back of the comb, the teeth of one 65 row being spaced apart beyond the roots from the teeth of an adjacent row to provide a longitudinal channel extending between each two contiguous rows from the tips of the teeth to a situation at the roots of the teeth, some of the teeth in one of 70 said rows being inclined in the plane of the row in relation to the teeth in an adjacent row and extending a substantially equal distance from the back of the comb, all the teeth 75 of the outer rows extending at their tips beyond the tips of the teeth of an inner row.

4. In a hair-comb comprising the combination with the back, of three substantially parallel rows of teeth arranged side by side 80 and held close together solely along the back of the comb, the teeth of one row being spaced apart beyond the roots from the teeth of an adjacent row to provide a longitudinal channel 85 extending between each two contiguous rows from the tips of the teeth to a situation at the roots of the teeth, at least some of the teeth of the middle row being inclined towards one end of the comb, and the teeth of the outer rows being substantially 90 perpendicular to the back of the comb and extending at their tips beyond the tips of the middle row.

5. In a hair-comb comprising the combination with the back of at least three substantially parallel rows of teeth arranged side by side and held close together solely 95 along the back of the comb, the teeth of one row being spaced apart in outwardly splayed relation beyond the roots from the teeth of an adjacent row to provide a longitudinal channel 100 extending between each two contiguous rows from the tips of the teeth to a situation at the roots of the teeth, the tips of the teeth in the outer rows being situated on a curve having its concavity facing away 105 from the back of the comb.

6. A hair-comb comprising in combination three substantially parallel distinct comb-units with their rows of teeth arranged side 110 by side and held close together solely along the back of the comb, the teeth of one unit being spaced apart beyond the roots from the teeth of an adjacent unit to provide a longitudinal channel 115 extending between each two contiguous units from the tips of the teeth to a situation at the roots of the teeth, the outer rows having the tips of their teeth situated on two arcuate lines of equal radius and the inner row having the tips of its 120 teeth situated on an arcuate line concentric with said two lines.

7. A hair-comb comprising in combination three substantially parallel separate comb-units with their rows of teeth arranged side 125 by side, the teeth of one unit being spaced apart beyond the roots from the teeth of an adjacent unit to provide a longitudinal chan-

nel extending between each two contiguous units from the tips of the teeth to a situation at the roots of the teeth, the tips of the teeth of the outer rows extending beyond the tips of the teeth of the inner row, means for holding said comb units together along their backs, and a means located at one

end of said comb permitting a relative displacement of the comb units upon the disengagement of said holding means.

10

In testimony whereof I have signed my name to this specification.

JACK STANSFIELD PICKFORD.
